ROBERT SIMPSON, OF GLASGOW, SCOTLAND.

LOOM FOR WEAVING TUFTED PILE FABRICS.

947,765.

Specification of Letters Patent. Patented Jan. 25, 1910.

Application filed June 7, 1909. Serial No. 500,742.

To all whom it may concern:

Be it known that I, ROBERT SIMPSON, a subject of the King of Great Britain and Ireland, and a resident of Glasgow, Scotland, have invented certain new and useful Improvements in Looms for Weaving Tufted Pile Fabrics, and of which the following is the specification.

This invention relates to looms for weaving tufted pile fabrics and of the type described in the earlier Patent No. 330,069. In the looms described in that specification the width of fabric which could be produced is limited for various reasons. For example, the yarn carrying spools cannot be of any great length as they would then be very liable to warp and thus throw the ends of the tuft yarn tubes out of alinement with the transferring nippers, which take the yarn tufts from the overhead spools and tuft tubes and cutting mechanism and insert them between the warps, with the result that tufts might be missed or misplaced and an imperfect pattern thereby produced; and if long spools were used of a construction heavy enough not to warp they would then not be easily handled by the attendants when threading the yarns through the tuft tubes, or when placing the spools and the tube frames in the carrying chains or removing them therefrom.

According to the present invention, when it is desired to increase the width of the fabric being woven, a number of the spools, with their tube frames, which will carry sufficient yarn for the width of fabric desired, are mounted in parallel carrying chains so as to be all in alinement, there being either a separate carrying chain for each end of each spool and tube frame as usual, or the chains may be modified so that one chain carries the opposite ends of two adjacent spools and tube frames. Since the spools and yarn tube frames are substantially as hitherto used in this type of loom, it follows that, when they are mounted in the chains in alinement, the row of tufts presented to the nippers is not continuous, but there is a gap between each spool with its tube frame and the adjacent spool with its tube frame in line with it. This gap allows the link of the chain from which the tube frames project to engage sprocket guide wheels on either side of the chain as in the narrow loom described in the earlier specification hereinbefore referred to, without

its being necessary to prolong the conveying chains unduly in a vertical direction to avoid reflex turns; or to have recourse to guides of special construction for turning corners, as has been necessary in former wide looms of this kind.

The improved loom is provided with sets of transferring nippers, there being the same number of sets as there is of spools in alinement, and, as because of the gaps between the ends of the spools the yarn tubes are not over the space between the warps into which the yarn tufts are to be inserted, each set of nippers is mounted in a frame carried on guide shafts so that a to-and-fro-movement across the loom may be imparted to the nippers, by cams and connections hereinafter described, in addition to the usual raising and lowering, opening and closing and semi-rotary movements necessary to be imparted to the nippers to enable them to transfer the yarn tufts from the overhead tuft tubes and insert them correctly in the warps. By this to-and-fro movement, as the nippers are being raised, turned up, and opened, to grip the tufts, the movable nipper frames are slid along from the center of the loom outward toward opposite sides of the loom until they come against a stop, the position of which is so regulated that when stopped each pair of nippers is exactly opposite its corresponding spool, and each end of yarn in each tuft tube is exactly opposite its corresponding nipper, there being then a gap between each set of nippers corresponding to the gaps between the overhead rows of spools and tuft tubes. The nippers are then closed to grip the yarn and draw off the required length which is severed by the knives in the usual way. Then, as the nippers are turned down and made to descend to insert the tufts of yarn into the shed, the movable nipper frames are again slid along the guide shafts inward toward the center of the loom until they come against other stops so arranged as to stop the nipper frames in such a position that each nipper is then opposite the space between the warps into which it has to be inserted in the usual way, in which position the nippers are close together in line and thus present one continuous and unbroken row of nippers, instead of several independent sets of nippers with gaps between.

The insertion and securing of the tufts between the warps is now performed as usual

and the nippers opened to leave the tufts in the fabric. The nippers are then closed and raised out of the shed and the process repeated. Each pair of nippers is kept closed, 5 against the action of springs tending to open them, by conical wedges on a rod or tube movable on end to insert or withdraw the cones, as in the earlier specification hereinbefore referred to, but as in the present construction the tube or rod carrying the 10 wedges has also to move on end with the nipper frames, it is actuated by special mechanism comprising a spring-controlled forked lever keeping the tube or rod carrying 15 the wedges in such position that the nippers are always closed unless the lever is being acted on by one or other of two tappets adjustable on a second rod or tube capable of sliding and rotating in the nipper frames, one tappet acting on the lever when the nipper frames are apart and beneath the tuft tubes and the other tappet when the nipper frames are close together and have inserted the tufts between the 20 warps. The mechanism for operating this sliding and rotating rod is hereinafter described, and more than one such rod may be employed if desired, or a rod and a tube may be used, also it is to be understood that 25 if desired one of the nipper frames may be kept stationary, that is, it may be raised and lowered and the nippers partly rotated as usual without having the to-and-fro movement referred to imparted to it.

30 In order that the invention and the manner of performing the same may be properly understood there are hereunto appended seven sheets of drawings to be hereinafter referred to, these drawings showing only 35 the parts of the loom necessary for the illustration of the present improvements.

In these drawings Figures 1 and 2, Sheets 1 and 2 are jointly a front elevation of the left hand side of the loom, Figs. 3 and 4, 40 Sheets 3 and 4, being jointly a sectional plan of the same side. These figures show only one complete spool with its tube frame and a portion of the next in alinement therewith, also one complete nipper frame and a portion 45 of the next, and it is to be understood that there may be any number of these parts in alinement according to the width of fabric the loom is designed to weave. Fig. 5, Sheet 5, is an end elevation showing the mechanism for giving the to-and-fro movement to the nipper frames. Fig. 6, Sheet 6, is also an end elevation showing the mechanism for giving longitudinal motion to the tappet rod, while Fig. 7, Sheet 7, is a similar view showing the mechanism for rotating that rod.

As shown in Figs. 1 and 2 of these drawings, the spools A and frames A¹ carrying the yarn tubes A² (only a few of which tubes 65 are shown to prevent confusion) are sub-

stantially as hitherto used in this type of loom, and the loom may be designed to weave a fabric of a breadth necessitating the use of any number of such spools and frames in alinement. The spools A and tube frames A¹ are mounted in endless parallel carrying chains B, B¹, which differ from such chains as hitherto constructed only in that the space between the inner sides of the shackle, or double link portion, 70 of the chain B¹ between the opposite ends of two adjacent spools A is wide enough to permit of receiving the ends of two adjacent tube frames A¹. If preferred, a separate carrying chain for each end of each spool A and tube frame A¹ may be provided. Only the lower part of one pair of these chains B, B¹, and three of the spools A and tube frames A¹ with half of the adjacent 75 three spools and frames which are in alinement therewith are shown, the yarn being omitted to avoid confusion. The endless chains B, B¹ are driven by sprocket wheels B² mounted on a shaft B³, other idle sprocket guide wheels (not shown) being located in any suitable position above the loom frame, all as in the earlier narrow loom hereinbefore referred to. When the spools A and yarn tube frames A¹ are mounted in the chains in alinement as 80 shown, the tubes A² through which the ends of yarn project are not continuous, so that there is a gap C in the row of tufts between each spool with its tube frame and the adjacent spool with its tube frame in line therewith. This gap C allows the link of the chain from which the tube frames project to go over the sprocket wheels as in the narrow loom referred to. In this way as 85 the tube frames and tubes are kept clear of sprocket wheels, on both sides of the chain instead of as hitherto in wide looms upon one side only, the desired sets of conveying chains, each carrying a large number of spools may be used without its being necessary to prolong the conveying chains unduly 90 in a vertical direction to avoid reflex turns; or to have recourse to guides of special construction for turning corners.

By the movement of the chains the spools A are presented successively in the proper positions for the yarn to be drawn from them and cut off in pieces of proper length to form the tufts, as in the narrow loom referred to. These tufts are inserted into the 100 warps by sets of transferring nippers, there being the same number of sets as there is of spools A in alinement. These nippers are substantially similar to those used in the narrow loom referred to, the jaws C¹, to 105 which are attached the plates of which the nipper fingers C² are constructed, being journaled on a sleeve C⁵ on a crank rod C³ the ends of which are carried by cranks C⁴ journaled in the outer ends of two arms D, only 110

one of which is shown, the other being at the opposite side of the loom. The opposite ends of these arms are secured on a rock shaft D^1 which works in bearings D^2 secured to the frames D^3 of the loom, so that the upward and downward movement of the nippers, that is, the movement between the tuft tubes A^2 and the warps (not shown) may be imparted by cam and lever connections (not shown) with one of the arms D as described in the earlier specification hereinbefore referred to, or it may be with both the arms D . The mechanism for giving the turning over or semi-rotary motion to the nippers is also similar to that described in the said earlier specification and therefore not shown in the present drawings.

As owing to the gaps C between the ends of the spools A , the yarn tubes A^2 are not over the spaces between the warps into which the yarn tufts are to be inserted, an additional movement to-and-fro across the loom has to be imparted to each set of nippers to enable them to transfer the yarn tufts from the overhead tuft tubes and insert them correctly in the warps. This is effected by causing the crank rod C^3 to pass through additional cranks E , these additional cranks being journaled in tubes E^1 passing through bearings in the outer ends of additional arms E^2 similar to the arms D , there being a pair of such additional arms for each set of nippers. Through the center of the tubes E^1 there extends a rod E^3 , the opposite ends of which are carried in bearings in the outer arms D , so that the tubes E^1 are capable of sliding on the rod E^3 for a purpose hereinafter described. Or the rod E^3 may be dispensed with, in which case the tubes E^1 may be replaced by rods. The inner ends of each pair of additional arms E^2 are carried on opposite ends of a sleeve G on the rocking shaft D^1 , so that each set of nippers are thus carried in a frame comprising the pair of arms E^2 and the sleeve G . The upward and downward movement imparted to the nippers as hereinbefore described is also imparted to this frame by a guide shaft G^1 passing through bearings in the arms E^2 and being secured at opposite ends to the outer arms D . To impart the desired to-and-fro movement to this frame and consequently to each of the set of nippers, face cams G^2 are provided on the main shaft G^3 , one for each nipper frame. These cams act upon a lever H which works on a fixed fulcrum H^1 and which is connected by a rod H^2 with one end of a bell crank lever H^3 , the opposite end of which is slotted to receive a pin J on the sleeve G . There is a separate cam G^2 for actuating each nipper frame, the one for actuating the frames at the outer sides of the loom being designed and proportioned as shown in Fig. 5, as these two frames

have to travel the farthest to bring their respective nippers correctly under the yarn tubes of their overhead spools. The intermediate cams are, of course, proportioned to suit the travel of the respective intermediate frames.

Each pair of nippers C^2 are kept closed, against the action of the usual springs J^1 tending to open them, by conical wedges J^2 as in the earlier specification hereinbefore referred to. These wedges are, in the present construction, carried on the tubes E^1 , and as these tubes must travel to-and-fro with the nipper frame G , E^2 they are actuated each by a forked lever J^3 , fulcrumed on a bracket J^4 formed on one of the arms E^2 , the opposite end of this lever being connected by a spring K to the opposite arm of each nipper frame, so that the tubes E^1 and consequently the wedges J^2 are kept in such position that the nippers are always closed unless the lever J^3 is being acted on by one or other of two prongs K^5 and K^6 on tappets K^1 adjustable on a rod K^2 capable of sliding and rotating in the nipper frames and side arms D as hereinafter described, one prong K^5 , when the nipper frames are apart and beneath the tuft tubes A^2 , being then in such position that it engages the side of the lever J^3 , so that when the rod K^2 is moved endwise the levers J^3 are so moved as to withdraw the wedges, and the other prong K^6 acting similarly on the levers when the nipper frames are closed together and have inserted the tufts between the webs.

The movement of the rod K^2 endwise and its rotation as desired, is produced by a cam L (Fig. 6) on the main shaft G^3 acting on a lever L^1 centered on the framing D^3 , this lever in turn being connected by an adjustable rod L^2 with one end of a bell crank lever L^3 centered on one of the arms D , the opposite end of this lever being connected to one end of the rod K^2 carrying the tappets K^1 , so that the rod is moved on end as desired. To give this rod the necessary rotation so that the proper projection acts on the forked lever J^3 at the proper time, a further cam M , shown in Fig. 7, is secured on the main shaft G^3 , and it acts through another lever M^1 centered on any convenient part of the framing D^3 , and carrying at its upper end a rack bar M^2 gearing with a pinion M^3 on the sliding rod K^2 , the pinion being connected with the rod by a feather and groove, and working in a slot in a plate M^4 secured on the guide rod G^1 , so that the pinion M^3 is prevented from moving endwise when the rod K^2 does.

In the position shown in the drawings, the nippers C^2 have been operated upon so that they are in their horizontal position and they are assumed to be moving upward. While rising, the nipper frames are slid

outward to opposite sides of the loom from the middle thereof by the mechanism hereinbefore described until they come each against a stop N on the rocking shaft D¹, the position of which stops is so regulated that when stopped each nipper frame G, E² is exactly opposite its corresponding spool A, and each end of yarn in each tuft tube A² is exactly opposite its corresponding nipper C², there being then a gap between each set of nippers corresponding to the gaps C between the overhead rows of spools and tuft tubes. During this upward movement, each set of nippers is turned up in the usual way. The rod K² with tappets K¹ is rotated by the mechanism described into such a position that one (K⁵) of the tappet prongs on it engages with the forked lever J³ in each nipper frame. Then a longitudinal motion is given to the rod so as to move the forked levers to withdraw the wedges J² from contact with the jaws C¹ of the nippers, and thus allow the nippers to open by the action of their springs J¹.

When the open nippers have been brought to their proper position, as hereinbefore described, the rod K² is then moved back again, withdrawing the tappet prongs K⁵ from contact with the forked levers J³, so that the springs K acting on the levers cause these levers to move the tubes E¹ carrying the cones J² on end, so that these cones are forced between the jaws C¹ of the nippers and the nippers are closed and grip the yarn, each individual nipper gripping its own yarn end as usual. The nippers now draw off the required length of yarn which is severed by means of knives, all as described in the earlier specification referred to. Then as the nippers are turned down and made to descend to insert the tufts of yarn they hold into the shed, the movable nipper frames are again slid along the guide shafts D¹, G¹ by the action of the cams G² and mechanism hereinbefore described, inward toward the center of the loom until they come against the adjustable stops N on the rocking shaft D¹ which stops are so arranged that each nipper is then opposite the space between the warps into which it has to be inserted in the usual way, in which position the nippers are close together in line and thus present one continuous and unbroken row of nippers instead of several independent sets of nippers with gaps between. The insertion and securing of the tufts between the warps is now performed as usual, and the opening of the nippers to leave the tuft in the fabric is accomplished by rotating the rod K² into the proper position, so that the other set K⁶ of tappet prongs encounter the forked levers J³, and then on the rod being given a longitudinal motion, these prongs move the forked levers so that these levers force the tubes E¹ carry-

ing the wedges J² endwise, so as to withdraw the wedges from the jaws C¹ of the nippers and allow the nippers to be opened by the action of their springs J¹ when the tufts have been inserted into the fabric. The nippers C² are then closed by reverse action on the rod K² carrying the tappets K¹ so as to again force the wedges J² between the jaws C¹ of the nippers C², which are then raised out of the shed and the process repeated.

What I claim is:—

1. In a loom of the type referred to for weaving tufted pile fabrics, a plurality of tuft yarn spool and tuft tube frame carrying chains, a plurality of rows of tuft yarn spools and tuft tube frames so carried by such chains that not only are the spools and tube frames in each row in alinement with each other but there is also a gap between each spool with its tube frame and the adjacent spool with its tube frame, a plurality of sets of tuft transferring nippers corresponding to the number of spools and tuft tube frames in alinement, and means for giving a to-and-fro motion across the loom to the sets of nippers.

2. In a loom of the type referred to for weaving tufted pile fabrics, a plurality of tuft yarn spool and tuft tube frame carrying chains, a plurality of rows of tuft yarn spools and tuft tube frames so carried by such chains that not only are the spools and tube frames in each row in alinement with each other but there is also a gap between each spool with its tube frame and the adjacent spool with its tube frame, a plurality of sets of tuft transferring nippers corresponding to the number of spools and tuft tube frames in alinement, means for giving a to-and-fro motion across the loom to the sets of nippers, and means for opening and closing the nippers.

3. In a loom of the type referred to for weaving tufted pile fabrics, a plurality of tuft yarn spool and tuft tube frame carrying chains, a plurality of rows of tuft yarn spools and tuft tube frames so carried by such chains that not only are the spools and tube frames in each row in alinement with each other but there is also a gap between each spool with its tube frame and the adjacent spool with its tube frame, a plurality of sets of tuft transferring nippers corresponding to the number of spools and tuft tube frames in alinement, the nippers being journaled in a frame comprising side arms and a sleeve on a rock shaft, a bell-crank lever connected to the nipper frame, a cam, and a lever and rod operated by the cam and connected to the bell-crank lever so as to impart a to-and-fro motion to the frame and consequently to the nippers.

4. In a loom of the type referred to for weaving tufted pile fabrics, a plurality of

- tuft yarn spool and tuft tube frame carrying chains, a plurality of rows of tuft yarn spools and tuft tube frames so carried by such chains that not only are the spools and 5 tube frames in each row in alinement with each other but there is also a gap between each spool with its tube frame and the adjacent spool with its tube frame, a plurality of sets of tuft transferring nippers corresponding to the number of spools and tuft 10 tube frames in alinement, the nippers being journaled in a frame comprising side arms and a sleeve on a rock shaft, a bell-crank lever connected to the nipper frame, a cam, and a lever and rod operated by the cam and connected to the bell-crank lever so as to impart a to-and-fro motion to the frame and consequently to the nippers and means 15 for opening and closing the nippers.
- 20 5. In a loom of the type referred to for weaving tufted pile fabrics, a plurality of tuft yarn spool and tuft tube frame carrying chains, a plurality of rows of tuft yarn spools and tuft tube frames so carried by such chains that not only are the spools and 25 tube frames in each row in alinement with each other but there is also a gap between each spool with its tube frame and the adjacent spool with its tube frame, a plurality of sets of tuft transferring nippers corresponding to the number of spools and tuft 30 tube frames in alinement, the nippers being journaled in a frame comprising side arms and a sleeve on a rock shaft, a bell-crank lever connected to the nipper frame, a cam, and a lever and rod operated by the cam and connected to the bell-crank lever so as to impart a to-and-fro motion to the frame and consequently to the nippers, springs 35 tending to open the nippers, and means for keeping them closed against the action of these springs comprising wedges on a spindle traveling with the nipper frame, a spring-controlled forked lever actuating the 40
- wedge spindle, a rod carrying two tappets 45 and means for moving this tappet rod on end and rotating it so that the tappets act in turn on the forked lever when necessary to cause the forked lever to withdraw the wedges from between the jaws of the nippers. 50
6. In looms of the type referred to and having a plurality of tuft transferring nippers, springs tending to open the nippers, and means for keeping them closed against the action of these springs comprising 55 wedges on a spindle traveling with the nipper frame, a spring-controlled forked lever capable of moving the wedge spindle endwise, a rod carrying two tappets acting on the forked lever, a bell-crank lever connected to the tappet rod, a cam, and a lever and rod operated by the cam and connected to the bell-crank lever so that an endwise movement may be imparted to the tappet 60 rod with means for rotating this rod. 65
7. In looms of the type referred to and having a plurality of tuft transferring nippers, springs tending to open the nippers, and means for keeping them closed against the action of these springs comprising 70 wedges on a spindle traveling with the nipper frame, a spring-controlled forked lever capable of moving the wedge spindle endwise, an endwise movable rod carrying two tappets acting alternately on the forked 75 lever, means for rotating this rod so that the tappets will act in turn and comprising a cam, a lever actuated thereby, a rack bar on the lever, a pinion gearing with the bar and rotating the endwise movable tappet 80 rod through a feather and groove.

In testimony whereof I have signed my name to this specification, in the presence of two subscribing witnesses.

ROBERT SIMPSON.
